UNITED STATES PATENT OFFICE.

MILTON S. ERLANGER, OF BALTIMORE, MARYLAND.

GARMENT-SUPPORTER.

No. 924,974.

Specification of Letters Patent.

Patented June 15, 1908.

Application filed June 16, 1908. Serial No. 438,383.

To all whom it may concern:

Be it known that I, MILTON S. ERLANGER, a citizen of the United States, residing at Baltimore, in the county of Baltimore City and State of Maryland, have invented certain new and useful Improvements in Garment-Supporters; and I do hereby declare the following to be a full, clear, and exact description of the invention, such as will enable others skilled in the art to which it appertains to make and use the same.

My invention relates to garment supporters, and has for its object the production of a supporter which although provided with the usual metal fasteners, yet, will effectually prevent any portion of the metal clasp from contacting with the body of the wearer.

To these ends my invention consists in the provision of an inexpensive cover for the metal clasp on the side next to the body, all as more fully disclosed hereinafter, and particularly pointed out in the claims.

Referring to the accompanying drawings forming a part of this specification, in which like numerals refer to like parts in all the views:—Figure 1, is a perspective view of my garment supporter, showing the side of the metal clasp which usually contacts with the body fully covered. Fig. 2, an edge view of the clasp portion of my supporter, showing how the flexible material itself is utilized to cover a metal face of the clasp, and Fig. 3, a detached plan view of that side of the clasp and supporter which contacts with the body of the wearer.

1, represents any suitable fabric constituting the body of my supporter; 2, any suitable means for attaching the same to the garment to be supported; and 3, a portion of any suitable metal clasp located near the attaching means 2.

In garment supporters of this kind, the clasp portion 3 is generally either left partially uncovered, in which case the body of the wearer is liable to be chafed; or else some expensive means is provided to prevent this chafing. In my supporter the extreme end 5 of a length of the material, passes through one of the slits 4 of the clasp 3; over the outer rim 6 of the same; through the slit in the attaching means 2, up through the same slit 4 and in the same direction as before; over the inner rim 7 of the same; over the face 8 of the clasp, as shown; through the other slit 4 of the clasp 3, covering the inner rim of said second slit; up and through any

suitable link 9; back over the outer rim of said second slit; and through the same in the same direction as before; and finally the other end 10 of the material may be secured to its bight 12, best shown in Fig. 2, or it may be secured to the opposite bight, or it may be left free as desired. The end 5 may also be secured to the bight 13, or the bight 14, of the material, or left free. It will thus be seen that the outer rim 6 of one slit 4 is covered by the bight 14 of the material; that the inner rim 7 of the same slit, the face 8, and the inner rim of the second slit is covered by the bight 15; and the outer rim of the second slit is covered by the bight 16 of the material. It results directly from this disposition of the parts that all portions of the metal clasp are covered on that side which contacts with the wearer; and the natural cushioning effect of the material is utilized to secure a soft and yielding action against the body of the wearer; thereby preventing in a simple and inexpensive manner all liability to chafe.

I do not wish to be limited to the exact details of construction and operation above disclosed, since it is evident that the same may be varied by those skilled in the art without departing from the spirit of my invention, as set forth in the appended claims.

What I claim is:—

1. In a garment supporter the combination of an attaching means 2 having a slit; a link; a clasp having a face and two slits 4, one of which is provided with an outer rim 6 having faces; and a single length of material, the end 5 of which is passed through one of said slits 4, over said outer rim 6, on one side thereof through said slit 4 of the said attaching means 2, up on the other side of said rim 6 and through the same slit 4 in the same direction as before, and then through said other slit 4, thereby covering the face of said clasp between said slits, as well as the faces of said rim, substantially as described.

2. In a garment supporter, the combination of an attaching means; a link; a clasp having a face portion and provided with a pair of slits having rims; and a single piece of material passing through one of said slits, and covering one of the rims thereof; then passing through the attaching means; then through said slit in the same direction as before covering the other rim of said slit and the face portion of the clasp; then through

the second slit covering one of the rims of said second slit; then through said link back through said second slit in the same direction as before, and covering the second rim 5 of said second slit, substantially as described.

3. In a garment supporter, the combination of an attaching means; a link; a clasp having a face portion and provided with a pair of slits having rims; and a single piece 10 of material passing through one of said slits and covering one of the rims thereof; then passing through the attaching means; then through said slit in the same direction as before, forming a bight 13 covering the 15 other rim of said slit and the face portion of

the clasp; then through the second slit covering one of the rims of said second slit; then through said link, forming a bight 12, back through said second slit in the same direction as before and covering the second rim of said second slit, one end of said material being secured to said bight 13, and the other end to said bight 12, substantially as described. 20

In testimony whereof, I affix my signature, in presence of two witnesses. 25

MILTON S. ERLANGER.
